AUTOMOBILE SEAT COVER

Arthur N. Landry, Jr., Lexington, Mass.

Application March 12, 1958, Serial No. 50,005

Term of patent 3½ years

(Cl. D15—8)

The single figure is a view in perspective of the automobile seat cover showing my new design.

The dominant features of my design reside in the portions shown by full lines in the drawing.

The side not shown is the same as the side shown while the back is plain and unornamented.

I claim:

The ornamental design for an automobile seat cover, as shown and described.
